4 Claims. (Cl. 18—8)

This invention relates to artificial silk materials and to a process of and apparatus for producing such materials. More particularly the invention is directed to artificial silk in which the filaments or threads thereof have a non-systematic denier variation and to an apparatus and process employed in their production.

The production of artificial yarns or threads and the utilization of the same in the formation of various types of fabrics presented many problems due in part to imperfections of the finished yarns or threads as prepared for the normal operations involved in the manufacture of knitted and woven fabrics. Almost from the very inception of the artificial silk industry these problems were recognized and there has been a constant and progressive advance in the art as a result of which artificial silk fabrics are now offered generally in competition with other standard fabrics. However, it has been found that while slight imperfections in the yarns, filaments or threads in the form of denier variations are objectionable, novel effects in a finished fabric may be produced if the filaments, yarns or threads are spun in a manner to produce accentuated non-systematic denier variations as distinguished from objectionable imperfections.

It has heretofore been suggested that the manufacture of artificial filaments with intentional systematic denier variations may be effected in a process in which the supply of the spinning solution to the spinnerets is systematically irregular. Additionally it has been suggested that the same result may be attained by applying a drag or braking action to the thread during its passage from the spinneret to the drawing off device. Further, it has been proposed to produce such denier variations in artificial threads by causing the spinneret during the spinning operation to alternately approach and retract from the drawing off device. Nevertheless, each of the heretofore proposed methods failed in one or more respects to accomplish the intended result. In the process in which the occurrence of denier variations is effected by varying the length of the thread passage between the spinneret and the drawing off device among other disadvantages the alternate approach to and retraction of the spinneret from the drawing off device lowers the quality of the thread due to the resistance encountered in the coagulating bath and, too, only relatively gradual systematic denier variations in the thread could be had by such a process because rapid movement of the spinneret would create a prohibitory motion in the bath.

The various known means for producing systematic denier variations are also unsatisfactory in that undesirable pattern effects are created in the fabrics made therefrom.

This invention has as an object the production of artificial filaments, yarns and threads, hereinafter referred to as "filaments," in which denier variations thereof are very pronounced and are non-uniform in length and occurrence. For the purposes of the present specification and claims, the thicker portions of the yarn will be hereinafter called "nubs."

This invention contemplates the formation of artificial silk filaments which have denier variations of relatively high degree while such variations are substantially free of systematic recurrence.

A mechanism by which artificial silk filaments may be manipulated during the spinning of the same for producing denier variations of the character specified also forms a part of this invention.

The mechanism contemplated by this invention in its specific preferred embodiment comprises a conoid drive, the shifting of the belt of which will change the frequency of engagement of electrical contact members which are initially responsible for the denier variations in the filaments.

Additionally this invention has as an object the provision of a process for the production of artificial silk filaments whereby novel effects will be produced in fabric in which they are incorporated, the novel effects resulting from the non-systematic variations in the denier of the filaments and the nubs formed at varying intervals. This is particularly pleasing because it has been found that materials wholly or partly fabricated of filaments having non-systematic, irregular denier variations are obtainable, even when dyed, printed or otherwise colored in a single operation. Moreover, they have varying dyeing characteristics and multitudinous unpredictable color effects.

Other objects and advantages will be apparent from the following detailed description when considered in connection with the accompanying drawings wherein:

Figure 1 is a diagrammatic view of one form of apparatus constructed in accordance with the invention for spinning artificial filaments in which the guide device introduced in the path of travel of the filaments from the spinneret to the collecting device for causing denier variations therein is shown in operative position;

Figure 2 is a diagrammatic illustration of part of the mechanism illustrated in Figure 1, but also includes the electrical circuits employed to effect the movement of the guide device;

5 Figure 3 is a sectional view taken on line 3—3 of Figure 2; and

Figure 4 is a detailed view taken on line 4—4 of Figure 2.

In referring to the drawings in detail the numeral 10 designates a spinneret positioned as shown in a coagulating bath 11. A thread guide 12 may be provided in the bath, although this is not necessary. From a suitable source (not shown) a spinning solution is caused to be extruded from the spinneret 10 as filaments 13 in accordance with any of the well known practices. In the case of a wet spinning process as illustrated the filaments are drawn through the coagulating bath 11 and may be then directed 15 around the thread guide 12 whereupon they are propelled to a draw off godet or collecting device 14 such as a bobbin or centrifugal bucket operated in accordance with the usual practice. Thread guide 12 may be omitted and the filaments led directly from the spinneret to the collecting device.

Between the draw off device 14 and spinneret 10 a pivoted lever or pendulum 15 is positioned. Lever 15 is fixed to a shaft 16 and mounted for oscillation therewith. At its free end lever 15 is provided with a guide roller 17. Arranged on lever 15 between guide roller 17 and the shaft 16 and preferably close to the shaft is another guide roller 18. Succeeding portions of filaments 13 in 30 their passage to the draw off device 14 after being directed around thread guide 12 are directed over guide roller 17 and then under guide roller 18 whereupon they pass through traverse guide 19 adjacent the draw off device.

40 In being propelled through the path as described the filaments are caused to follow the course provided by the arrangement of lever 15 and guide rollers 17 and 18 and since lever 15 is oscillated within a varying sector during a spinning operation, succeeding portions of the filaments will be caused to extend and travel in paths of different lengths between spinneret 10 and draw off device 14. As guide roller 18 is immediately adjacent shaft 16 the oscillation of its carrying lever 15 does not greatly effect a change in the length of the filament path of travel between roller 18 and the draw off device.

50 Guide roller 17 has its shaft mounted for adjustment within slot 20 in lever 15 and since it is the movement of guide roller 17 which is primarily responsible for the change in the filament path, similar adjustability of guide roller 18 is not necessary.

During a spinning operation it is desirable 60 sometimes to limit the extremes of oscillation of lever 15 and as will appear from Figures 2 and 4 of the drawings shaft 16 is provided with a fixed extension 21 which is adapted to engage with adjustable stops 22 and 23 respectively at its extreme upper and lower positions. Stops 22 and 23 are supported by plate 24 which is secured to the support for shaft 16.

The operating mechanism for causing lever 15 to oscillate is constructed in a manner which will 70 cause the lever to oscillate irregularly and non-systematically within a varying sector. This mechanism is provided with a main electrical circuit 25 and an auxiliary control circuit 26. Control circuit 26 includes an electrical power source 28, an electro-magnet 29, armature 30,

normally held out of contact by spring member 27, conductor rails 31 and 32, connecting leads 33 and 34 and wiping contacting members 35 and 36 mounted on the respective rails 31 and 32 for sliding movement thereon. When member 35 contacts with member 36 the auxiliary circuit 26 is closed and the electro-magnet 29 is energized for the purpose to be hereinafter described.

A driving shaft 37 mounted in bearings 38 is arranged adjacent to and parallel with rail 31 and 10 this shaft is adapted to be rotated through the medium of a pulley 39 by a source of power (not shown). At the end remote from pulley 39, shaft 37 has keyed thereto a gear 40 which is maintained in constant engagement with a wide sliding gear 41. Gear 41 is formed on the hub of a cone 42 of a friction clutch 43 and the hub is mounted for rotation upon a shaft 44 which is mounted for rotation in bearing 45. Fixed to shaft 44 is a friction clutch member 46 which is 20 adapted to be engaged by the cone 42, which member 46 is provided with a sprocket 47 having mounted thereon a chain 48.

Chain 48 is mounted over a sprocket 49 which is in turn keyed to shaft 16 whereby the lever 15, 25 shaft 16, sprockets 47 and 49 and chain 48 are all caused to move in unison. As is shown in Figure 2 any desired number of levers 15 may be mounted on shaft 16, depending upon the number of spinning points employed.

30 The hub of cone clutch member 42 is provided with a peripheral groove 50 in which is engaged a clutch yoke 51 formed on lever 52 which is pivoted at 53. Lever 52 is biased by spring 54 to cause the frictional engagement of cone 42 and member 46 of the clutch. Therefore, in normal operation the clutch members are engaged and the power applied to shaft 37 through pulley 39, is transmitted to the cone 42 and due to its frictional engagement with clutch member 46, the 40 latter through the medium of the sprockets and chain, maintains shaft 16 in a position where extension 21 is in its upper position in engagement with stop 22. Consequently levers 15 would be normally biased to the uppermost extreme of 45 the path of oscillation.

55 Pivoted lever 52 has thereon the armature 55 of electro-magnet 56 the latter forming a part of the main circuit 25. Circuit 25 includes a source of electrical energy 57, leads 58, 59 and 60 and a quick action switch 61. Upon the closing of switch 61 by contact of members 35 and 36, the main circuit is energized and the electro-magnet 56 overcomes the bias of lever 52 effected by spring 54 and thereby moves cone 42 so as to disengage clutch 43. This allows lever 15 to drop 55 of its own weight.

60 As has been discussed above, when the auxiliary circuit 26 has been energized in response to the contacting of members 35 and 36 which in turn are actuated by the conoid drive 68—69, electro-magnet 29 causes the movement of armature 30 against the thrust of spring member 27 closing circuit 25. It will be seen that the contacting of members 35 and 36 will be irregularly 65 intermittent because of the change speed mechanism represented at 68 and 69 in its action on the cam wheels 62 and 63. Since the main circuit 25 is energized only upon the energization of the auxiliary circuit 26, the non-systematic closing of the auxiliary circuit will necessarily result in a non-systematic closing of the main circuit which in turn will result in a corresponding intermittent bias of lever 52 controlling clutch 43 operatively connected to the guide roller 17 which is 70 75

directly responsible for imparting the irregularly recurring nubs to the extruded filaments.

This irregularity of engagement of contacting members 35 and 36 is caused by the variable rotation of grooved cam wheels 62 and 63 respectively, the grooves of which wheels have received therein pins 64 and 65 extending respectively from contact members 35 and 36. Cam wheel 62 is fixedly supported on shaft 37 and cam wheel 63 is fixedly supported upon a shaft 66 which is positioned parallel to rail 32 in a manner corresponding to the relative arrangement between rail 31 and shaft 37. Shaft 66 is mounted in bearings 67 and a cone pulley 68 is fixed thereto.

15 A similar cone pulley 69 in reverse position is fixed to shaft 37 and the two pulleys are connected by a shiftable belt 70. The actuation of contacting members 35 and 36 by the mechanism just described will be effected upon the application of power to pulley 39 causing shaft 37 and cam wheel 62 to rotate. Through the medium of cones 68 and 69 and belt 70, shaft 66 and cam wheel 63 will be caused to rotate at the same or different speeds in response to the position of belt 70. In order to obtain the non-systematic contact of the members, the shafts are operated at different speeds and the relative speeds may be changed by automatic or mechanical shifting of the belt. Due to the relative movements of 25 the shafts and the cam wheels the period of duration of contact and the frequency of contact of the members 35 and 36 is continuously changed. This causes a difference in the sized arcs through which the lever 15 passes. The contact members 30 at times will move in the same direction at different speeds, in the same direction at the same speed, in opposite directions at different speeds and in opposite directions at the same speed.

In the practising of the present process by 40 the employment of the mechanism illustrated the spinning solution is extruded through the spinneret 10 and the filaments thus formed are drawn through the coagulating bath 11 and around thread guide 12. In the meantime power 45 is applied through the medium of pulley 39 and in the manner previously described lever 15 is caused to proceed toward its upper extreme limit of its path of oscillation while the clutch members are in frictional engagement. Shafts 37 and 50 66 are caused to be operated at different relative speeds by means of the conoid drive composed of cones 68 and 69 and belt 70 and this in turn thus rotating cam wheels 62 and 63 and resultantly propelling contacting members 35 and 36 along 55 the rails 31 and 32.

Upon contact of the members 35 and 36 auxiliary circuit 26 is closed and electro-magnet 29 is energized. Armature 30 is then moved to close switch 61 of the main circuit thereby energizing 60 electro-magnet 56 thus actuating lever 52 which disengages the clutch members. Upon disengagement of the clutch members, lever 15 by force of gravity will drop to its lower extremity of its path of oscillation.

65 As contact members 35 and 36 are further propelled to a position out of mutual engagement both the auxiliary circuit 26 and the main circuit 25 will be opened and lever 52 will be biased by spring 54 which will cause frictional engagement of cone 42 and clutch member 46 whereupon lever 15 will again proceed toward its upper position until the contact members again close the circuit.

In this manner succeeding portions of the 70 freshly extruded filaments are caused to be

stretched to different degrees and nubs formed at irregularly spaced points therealong, because as the lever 15 rises, the path of travel and stretch varies and when lever 15 falls, the tension is released and thick portions or nubs 5 created adjacent the spinnaret. Succeeding portions of the filaments will be of non-systematically varied denier in response to the non-systematic oscillation of lever 15, the movement of the lever being initially under the control of the 10 irregularly recurring contact of members 35 and 36. Moreover, when lever 15 drops of its own weight, the thread tension will be released and a "lump" of filaments will form and coagulate adjacent the spinnaret. 15

While the invention applies particularly to filaments of irregularly varying denier produced by the wet or coagulation method and composed of reconstituted cellulose, such as viscose or cuprammonium silk, it may be applied likewise to 20 filaments produced by the dry or evaporative method, more specifically filaments or threads having as a base cellulose acetate or other cellulose derivatives.

It is intended that the process described, except for that portion thereof relating to the non-systematic production of irregularly varying denier, shall be conducted according to the well known practices in the art.

The methods and apparatus described above 30 are merely representative and it is intended to include all methods and forms of apparatus as will fall within the scope of the following claims.

What is claimed is:

1. An apparatus for producing artificial silk 35 comprising means for forming filaments, a draw-off device, a thread guide mounted for vertical oscillation interposed in the path of travel of the filaments between the forming means and the draw-off device, a main electric circuit for 40 effecting movement of the thread guide when closed, a second control circuit for closing the main circuit, and constantly variable mechanical means for opening and closing the control circuit at non-systematic intervals to cause corresponding periods of energization of the main circuit and resultant irregular and indefinite upward movement of the thread guide, the downward movement being controlled by gravity. 45

2. In an apparatus for producing artificial silk 50 including means for forming filaments; a draw-off device, a thread guide mounted for oscillation interposed in the path of travel of said filaments intermediate the forming means and the draw-off device, said guide being operatively connected to a friction clutch, means for irregularly operating said clutch to move said guide in one direction and means for moving the guide in the opposite direction. 55

3. An apparatus for producing artificial filaments comprising means for forming filaments, a draw-off device, a thread guide interposed in the path of travel of said filaments from said forming means to said draw-off device, means for causing said guide to move irregularly in one direction including a friction clutch operatively connected to the guide, an electric circuit for effecting actuation of the clutch, a second electric circuit containing wiping contactors for controlling the energization of the first circuit, and irregularly driven rotating cams irregularly moving the contactors to cause opening and closing of the second circuit and means for returning the guide to its original position. 60

4. An apparatus for producing artificial fila- 75

ments comprising means for forming filaments, a draw-off device, a guide for said filaments in their path of travel intermediate the forming means and the draw-off device including a controlled throw oscillating lever with guide rollers mounted thereon, means to irregularly raise the lever of the guide comprising a friction clutch operatively connected thereto, an electric circuit

controlling the action of the clutch and a second electric circuit controlling said first circuit, said second circuit being energized upon the contacting of sliding wiping contactors which are actuated by irregularly driven rotating cams and 5 means to lower the lever of the guide.

GUSTAV A. M. HEIM.
